UNITED STATES PATENT OFFICE.

RICHARD P. PARK, OF MELBOURNE, VICTORIA, AUSTRALIA.

MACHINE FOR REDUCING ORE.

1,281,646.

Specification of Letters Patent. Patented Oct. 15, 1918.

Application filed May 28, 1918. Serial No. 237,115.

To all whom it may concern:

Be it known that I, RICHARD PICKUP PARK, a subject of the King of Great Britain and Ireland, and a resident of the city 5 of Melbourne, in the county of Bourke, State of Victoria, Commonwealth of Australia, (whose post-office address is 317 City road, South Melbourne, in the said city of Melbourne,) have invented certain new and useful 10 Improvements in and Connected with Machines for Reducing Ore, of which the following is a specification.

This invention relates to machines for reducing ore, the primary object being to 15 provide means whereby a maximum of ore may be pulverized to any desired degree in a minimum of time.

The invention is adapted for the reduction of many and various kinds of ore and has 20 been found particularly advantageous in the treatment of mica bearing material which has hitherto been regarded as one of the most difficult of ores to treat.

According to the invention the ore is 25 fed on to a revolving ring or table which carries it beneath a succession of crushing and grinding rollers which are adapted to gradually reduce the ore to any desired state of subdivision. This gradual reduction is 30 due to the arrangement of the rollers in stepped relationship to the table as will be hereinafter better understood.

A material feature of the invention is the 35 driving of the crushing and grinding rollers at a considerably higher speed than the speed of rotation of the table. This has the effect of not only crushing the material by direct compression between the rollers and table but sets up a shearing or grinding 40 action which reduces the ore in a highly effective manner.

A further feature of the invention resides 45 in the provision of means for adjusting the rollers to or from the table whereby the degree of fineness of the resultant product may be regulated to any desired degree. By this means the objectionable "slumping" which frequently occurs during the subsequent flotation treatment of the reduced material is obviated. This "slumping" or 50 floating away of the material on the surface of the liquid used in separation is due to the

reduction of the ore to too fine a degree and with most types of ore mill cannot be prevented.

55

This invention also provides for regulating the pressure on the crushing and grinding rollers and for allowing them to rise and pass any foreign obstruction such as a hammer head, which might be passed into the 60 machine with the ore.

Referring to the drawings which form a part of this specification:—

Figure 1 is a sectional view of the invention taken approximately on the line A—A 65 of Fig. 2. Parts are broken away and removed for convenience of illustration.

Fig. 2 is a plan of Fig. 1 portion being broken away to reveal a complete set of crushing and grinding rollers and portion 70 of a floating ring by which the said rollers are driven.

Fig. 3 is a side elevation partly in section looking at the right hand side of Fig. 2.

Fig. 4 is a diagram showing the stepped 75 relationship of the rollers to the table whereby the material is gradually reduced step by step from the first roller on the right to the last roller on the left.

Fig. 5 is a detail view on an enlarged scale 80 showing portion of the floating ring.

Fig. 6 is a detail view on an enlarged scale showing portion of the revolving table which engages with and drives the floating ring.

Fig. 7 is an end view on an enlarged scale 85 of a boss and the second and third guide rollers which form a track for the floating ring.

Fig. 8 is a plan view of portion of a race showing the first guide rollers which support the revolving table.

On reference to the drawings it will be seen that 2 indicates the foundation plate or base upon which rest standards 3. Mounted upon the said standards is a stationary 95 race 4 having at its bottom a wearing ring 6. Disposed within said race are a pair of removable hoops 7 which form bearings for the spindles of first guide rollers 8.

Mounted in suitable bearings 9 and 11 are 100 main driving shafts 12 carrying main driving pinions 13.

Engaging the main driving pinions 13 is a toothed ring 14. This is fixed to the bottom

of a revolving ring or table 16 which ring or table carries lower wearing rings 17 which rest upon the first guide rollers 8. Carried by the revolving ring or table is a removable liner, 18, having a circumferential upstanding lip 19. This liner is constructed of material suitable to form a grinding surface for the table. Attached to the outside of the revolving table is an upstanding ring 21. 5 This is vertically adjustable in relation to the surface of the table by means of adjusting screws 23 and slots 24 and prevents material escaping over the outer edge of the table. In wet crushing operations this ring 10 can be raised to a considerable height above the surface of the table to prevent the overflow of the slime.

Upstanding from the interior of the table are a pair of inner revolving dust rings 26 20 which prevent the access of dust or other foreign matter to the toothed gearing hereinafter referred to which drives the crushing and grinding rollers. Between the dust rings 26 are a series of openings 27 through 25 which such foreign matter may escape. Protruding from the inner circumference of the revolving table are a series of vertical keys 28 which engage keyways in the floating ring hereinafter referred to. 30 Rotated by the revolving ring or table is a floating ring 29. This is provided with a series of vertical keyways 31 (Fig. 5) to accommodate the keys 28 on the table. The upper surface of the floating ring is provided with a toothed ring 32. Around the bottom of the floating ring extends a lip 33 inside which is a runway 35 for a series of second guide rollers hereinafter mentioned.

Upstanding from the foundation plate are 40 a series of guides 34. Between these guides is situated the lower end of a stationary ballast holder 36 which is prevented from rotating by said guides. At each corner of the bottom of the ballast holder is a lug 37. 45 Through this extends a vertical threaded hole to accommodate an adjusting screw 38. These adjusting screws are provided with rounded heads which rest upon the foundation plate. The said screws may be locked 50 in desired positions by lock nuts 41. Passing through the bottom of the ballast holder is a central hole through which passes a vertical tension bolt 43 which at its lower end is universally connected to the foundation plate by means of a ball and socket or other joint 44.

Surrounding the lower end of the tension bolt is a sleeve or distance piece 47 above which is a loading spring 48. Upon the 60 loading spring rests a washer 49 above which are adjusting nuts 51 which engage the threaded upper end 52 of the tension bolt to enable the strength of the spring 48 and the load on the crushing and grinding 65 rollers to be adjusted.

Protruding from the side of the ballast holder are a series of studs 53 upon the outer ends of which are mounted second guide rollers 54 upon which rests the floating ring 29. Surrounding and fixed to each stud 53 70 is a boss 56 which carries a pin 57. Around these pins rotate third guide rollers 58 which bear against the inner surface of the floating ring as seen in Fig. 1.

Surrounding the top of the ballast holder 75 is a flange 59 upon which rests a stationary depending hood 61. Formed on the said hood is an inner stationary dust ring 65 and a series of inclined bearings 62, these accommodate the inner ends of inclined shafts 63 the 80 outer ends of which are supported by outer bearings 64 at the lower ends of brackets 66.

The brackets 66 are attached to an enlarged mouth or hopper 67 which converges downwardly to the top of the ballast holder. 85

Mounted upon each of the inclined shafts 53 is a crushing and grinding roller. These rollers may be arranged in one, two or more sets or series, each series providing an independent ore reducing mechanism. In the 90 drawings two series of three crushing and grinding rollers are shown each series comprising a first or smallest roller 68, a second or larger roller 69, and a third or largest roller 71, but I do not limit myself to 95 any particular number of rollers which number will depend upon the size of the machine and the circumstances surrounding its use. As will be seen in Fig. 4 the centers of the rollers are disposed upon a single 100 horizontal line but owing to their varying diameters the space which exists between the periphery of each roller and the surface of the revolving table gradually diminishes from the first roller 68 to the last roller 71, 105 by this stepped formation the ore is gradually reduced to the required degree of fineness which is represented by the distance between the periphery of the last roller 71 and the surface of the table. 110

Each crushing and grinding roller tapers toward the center of the table and is provided with a removable shoe 81 of material suitable to form a crushing surface. The shoes are provided with inturned flanges 82 115 which are screwed or otherwise secured to the body of the roller. The crushing and grinding rollers are stationary as regards their disposition over the table but are driven by means of bevel pinions 83 engaging 120 the teeth 32 upon the floating ring, the ratio between the toothed ring 32 and the pinions 83 being such that the rollers are driven at a considerably higher speed than the speed of rotation of the table. 125

The ore is fed on to the revolving table through feeding chutes 84 disposed in front of each of the first rollers 68 of each series. In some cases it may be desirable to provide the periphery of these first rollers with a 130

series of axial grooves to better pick up the larger pieces of ore falling through the chutes on to the table.

Situated behind each of the final rollers 71 is a discharge chute 86 into which the pulverized material is diverted by means of diagonal stop plates 87. These stop plates are held tightly down upon the surface of the table by springs 88 the rear end of 10 the stop plates being pivoted at 85 to the bottom of the feed chutes or other stationary part of the machine.

Disposed behind each of the crushing and grinding rollers is a scraper 89 which removes any of the crushed material which 15 might remain clinging to the surface of the roller.

The scraper of the final roller of each series is in the form of a combined scraper 20 and guard 91 seen clearly in Fig. 3. This besides scraping the material from the roller prevents dust or slime being thrown up at the discharging point.

Attached to extensions from the outer 25 bearings 64 is an outer stationary dust ring 92 which partially surrounds the table being cut away as shown in Fig. 2 to allow the pulverized material to pass off the table into the discharge chutes.

30 In operation the main driving pinions drive the toothed ring 14 and with it the revolving ring or table which runs freely upon the first guide rollers 8. By reason of the keys 28 the floating ring is also rotated running freely upon the second and third guide rollers. As the floating ring rotates, its toothed ring 32 drives the bevel pinions 83 which in turn drive the shafts 63 and the crushing and grinding rollers. 35 It will thus be seen that while the floating ring and the crushing and guiding rollers are driven by the table they are capable of independent vertical movement in relation thereto.

40 As the ore is fed through the feed chutes 84 it falls upon the table in front of the first crushing and grinding rollers 68 beneath which it is carried and partially reduced. It is then carried forward by the 45 table and successively further reduced by the intermediate and final crushing and grinding rollers from which latter it emerges in the required state of subdivision.

50 After the reduced material has passed the final rollers it is carried forward by the table until it encounters the diagonal stop plates 87 against which it banks up and is diverted over the ring 21 into the discharge chutes.

55 It will be seen that by manipulation of the adjusting screws 38 the floating ring and the crushing and grinding rollers may be raised or lowered bodily in relation to the table. By this means wear between the rollers and 60 the table may be taken up and furthermore

the rollers may be so adjusted as to reduce the material to any desired degree. This adjustment may be effected by raising the rollers as aforesaid by the operation of the adjusting screws and then placing a gage 70 between the largest or final rollers and the table this gage corresponding to the size of the pulverized material which it is desired to produce. The rollers may then be lowered by reverse movement of the adjusting screws until they rest or almost rest upon the gage which is then removed. The lock nuts 41 are then tightened and the final rollers 75 71 are set at a distance above the table equal to the size of the resultant material while the first and intermediate rollers are set at a proportionate distance higher.

80 By the foregoing means the material may be reduced to the finest of powders by lowering the rollers sufficiently close to the table 85 or as is frequently desired with certain ores such as tin, wolfram or molybdenite the machine may be adjusted to produce a coarser product which will not be subjected to the objectionable "slumping" before mentioned.

90 It will further be seen that should an obstruction be conveyed into the machine with the ore it will on encountering the crushing and grinding rollers cause them to rise thereby allowing the obstruction to pass 95 without injuring the mechanism. The universal connection 44 permits the ballast holder and other parts to cant slightly should the machine rise more on one side than the other. The loading spring 48 will 100 exert sufficient pressure on the crushing and grinding rollers to fulfil most requirements and this pressure may be regulated by adjusting the nuts 51 on the tension bolt. Should it be desired, however to load the 105 rollers beyond the strength of the spring any suitable ballast material may be introduced into the ballast holder through its enlarged mouth 67.

110 The invention provides a highly efficient mill which as above stated may be regulated to reduce ores to various degrees of subdivision and allows of obstructions passing without injuring the parts. The arrangement by which the crushing and grinding 115 rollers are rotated in the same direction but at a faster speed than the table constitutes a material feature of the invention. Its effectiveness also depends largely upon the manner in which the rollers gradually reduce the ore thereby distributing and lightening the work which the machine is called upon to perform. It will be obvious that other means may be adopted to obtain this latter result such as the use of rollers of equal 120 diameters but mounted at different heights above the table. Finally the construction of the machine is such that it may be easily dismantled and thus lends itself particularly to transport purposes which is of particular 130

advantage considering the inaccessible localities in which such machines are frequently needed.

Having now described my invention what I claim as new and desire to secure by Letters Patent is:

1. In a machine for reducing ore, a revolving ring or table, a floating ring driven by said table and capable of moving vertically and independently of said table, crushing and grinding rollers coöperating with said table, said floating ring being adapted to drive said rollers at a different peripheral speed to the speed of rotation of the table.
2. In a machine for reducing ore, a revolving ring or table, crushing and grinding rollers coöperating with said table, means whereby said rollers are driven at a higher peripheral speed than the speed of rotation of the table, a ballast holder supporting the crushing and grinding rollers and a loading spring located within said ballast holder and pressing the crushing and grinding rollers toward the table.
3. In a machine for reducing ore, a revolving ring or table, crushing and grinding rollers coöperating with said table, means whereby said rollers are driven at a higher peripheral speed than the speed of rotation of the table, a ballast holder supporting the crushing and grinding rollers, a loading spring located within said ballast holder and pressing upon said rollers, and a central tension bolt passing through the loading spring and universally connected at its lower end to the foundation of the machine.
4. In a machine for reducing ore, a revolving ring or table, a floating ring driven by said table and capable of independent vertical movement in relation thereto, a series of crushing and grinding rollers arranged near and above the surface of said table, means for exerting pressure upon said rollers, means for adjusting said pressure and means for vertically adjusting the floating ring and the rollers in relation to the table.
5. In a machine for reducing ore, a revolving ring or table, a floating ring driven by said table and capable of independent vertical movement in relation thereto, a centrally situated ballast holder, guide rollers carried by said ballast holder and adapted to support said floating ring, a series of crushing and grinding rollers arranged near and above the surface of the table and driven by said floating ring, a tension bolt located at the center of said ballast holder and universally connected at its lower end to the foundation of the machine, an adjusting loading spring surrounding said bolt and adjusting screws adapted to raise

and lower the ballast holder and the crushing and grinding rollers.

6. In a machine for reducing ore, a revolving ring or table, keys carried by said table, a floating ring having keyways to accommodate said keys, a toothed ring carried by said floating ring, a ballast holder, guide rollers carried by the ballast holder and supporting the floating ring, adjustable loading means adapted to press upon the ballast holder, means for vertically adjusting the ballast holder, a hood depending from the top of the ballast holder, an enlarged mouth or hopper above said hood, inclined shafts supported by said hood, a pinion carried by each of said shafts and engaging said toothed ring and a crushing and grinding roller carried by each said shaft, said crushing and grinding rollers being arranged near and above the surface of the table for the purpose set forth.

7. In a machine for reducing ore, a revolving ring or table, keys carried by said table, a floating ring having keyways to accommodate said keys, a toothed ring carried by said floating ring, a centrally located ballast holder, a tension bolt passing through said ballast holder and universally connected to the foundation of the machine, guide rollers carried by the ballast holder and supporting the floating ring, an adjustable loading spring surrounding the tension bolt and adapted to press upon the ballast holder, means for vertically adjusting the ballast holder, a hood depending from the top of the ballast holder, an enlarged mouth or hopper above said hood, inclined shafts supported by said hood, a pinion carried by each of said shafts and engaging said toothed ring, a crushing and grinding roller carried by each said shaft, and dust excluding means surrounding the pinions and toothed ring.

8. In a machine for reducing ore, a revolving ring or table, a series of crushing and grinding rollers arranged near and above the surface of the table, means whereby said rollers are driven in the same direction as but at a higher peripheral speed than the speed of rotation of the table, and a vertically adjustable ring attached to the outside of the revolving table for the purpose set forth.

9. In a machine for reducing ore, a substantially horizontal revolving table, means to drive the table, a ballast holder arranged near the central portion of the table, adjustable supporting means for the ballast holder whereby it may be moved vertically with relation to the table, means including a yielding element to normally retain the ballast holder against movement and allowing of restricted vertical and lateral movements, shafts secured to the ballast holder

and extending substantially radially above the table, rollers carried by the shafts and coacting with the table, pinions secured to the shafts to drive them and gearing engaging the pinions to drive them and having vertically adjustable connection with the table to be driven thereby.

10. In a machine for reducing ore, a substantially horizontal annular revolving table, means to drive the table, a substantially vertical ballast holder arranged within the annular table, means to vertically adjust the ballast holder with relation to the table, shafts secured to the ballast holder and ex-

tending substantially radially above the 15 table, rollers secured to the shafts and coacting with the table, pinions secured to the inner portions of the shafts, a ring gear surrounding the ballast holder and disposed between the same and the table and engaging the pinions to drive them, supporting means for the ring gear carried by the ballast holder, and slidable connections between the ring gear and annular table.

In testimony whereof I affix my signature. 25
R. P. PARK.
